DISPENSING CLOSURE

Livingston C. Douglas, Leonia, N.J., and Gilbert De Wayne Miles, Ossining, and Russell Park McGhie, Somers, N.Y., assignors to Colgate-Palmolive Company, New York, N.Y.

Filed Jan. 7, 1971, Ser. No. 104,837

Term of patent 14 years

Int. Cl. D9—07

U.S. Cl. D9—278

FIG. 1 is a side elevational view of a dispensing closure embodying our new design, the opposite side being a mirror image of the side shown;

FIG. 2 is a top plan view thereof;

FIG. 3 is an elevational view thereof as seen from the left side of FIG. 1;

FIG. 4 is an elevational view thereof as seen from the right side of FIG. 1;

FIG. 5 is a bottom plan view thereof; and

FIG. 6 is a perspective view with the cover portion in open position.

We claim:

The ornamental design for a dispensing closure, as shown and described.
